Primary Examiner — Philip S Hyder

(57) **CLAIM**

The ornamental design for a prying tool head, as shown and described.

DESCRIPTION

FIG. 1 is a front view of a prying tool head showing my new design;

FIG. 2 is a rear view of the prying tool head;

FIG. 3 is a right side view of the prying tool head, a left side view being a mirror image thereof;

FIG. 4 is a top view of the prying tool head;

FIG. 5 is a bottom view of the prying tool head;

FIG. 6 is a top front side perspective view of the prying tool head;

FIG. 7 is a top rear side perspective view of the prying toolhead; and,

FIG. 8 is a bottom front side perspective view of the prying tool head.

The broken lines are illustrative of portions of the prying tool head forming no part of the claimed design.
